UNITED STATES PATENT OFFICE.

ALFRED GRIFFITH, OF McALESTER, OKLAHOMA.

FASTENER FOR COLLARS AND THE LIKE.

1,258,112.

Specification of Letters Patent.

Patented Mar. 5, 1918.

Application filed September 27, 1917. Serial No. 193,538

To all whom it may concern:

Be it known that I, ALFRED GRIFFITH, a citizen of the United States, and a resident of McAlester, in the county of Pittsburg and State of Oklahoma, have invented a new and useful Improvement in Fasteners for Collars and the like, of which the following is a specification.

My present invention relates generally to garment fasteners, and more particularly to fasteners designed for securing collars and the like, my object being to provide a button carrying member capable of utilization for instance, at the rear of the neck-band of a shirt, for effective use irrespective of the usual button-hole at this point of the collar band.

As is well known, the collar band of the usual shirt has at the rear portion thereof, a separated section of material at its outer part, which section of material carries the button-hole in order that the base of a collar button extended through the button-hole, will lie between the main portion of the neck-band and said separate section of material. My invention aims to provide a fastener for utilization for instance, with a neck-band so constructed, irrespective of whether or not the usual button-hole is present, and operating to secure the rear portion of a collar entirely independent of such button-hole.

To this end, my invention consists in the fastener of the construction to be now described, shown in the accompanying drawing, wherein:

Figure 1 is a detail perspective view with the two plates held slightly apart.

Fig. 2 is a side view with the top in normal position.

Fig. 3 is an inner face view of one of the plates.

Fig. 4 is an outer face view of the other of said parts.

Fig. 5 is a vertical sectional view taken substantially on line 5—5 of Fig. 4, and

Fig. 6 is a detail perspective view of the hinge pin.

Referring now to these figures, my invention consists in a pair of plates 10 and 11, normally held in face to face relation, and which may be generally of the flatiron shape as shown, the inner opposing faces of which are roughened as respectively indicated at 12 and 13, for a purpose to be presently described.

At its larger end, the plate 10 has side ex-

tensions 14 bent to receive the extremities of a hinge pin 15 the particular construction of which is shown in Fig. 6.

This hinge pin 15 has a central enlargement 16 provided with a flattened face 17, and the other plate 11 has at its enlarged end a pair of extensions 18 also adapted to receive the extensions of the hinge pin and to engage the latter at opposite sides of the central enlargement 16 thereof and between the extensions 14 of the plate 10.

In use, the hinge pin 15 is preferably in immovable relation to the plate 10 and is for this purpose rigidly united with the extensions 14, in order that the flattened surface 17 of the hinge pin enlargement 16 may be in definite relation to the plate 10, at all times.

The plate 11 is further provided with an extension 19 projecting beyond its enlarged end at a point between its extensions 18, the free end of which forms a spring engaging the flattened surface 17 of the hinge pin enlargement 16 so as to normally urge the plate 11 toward and into engagement with the plate 10, these plates being as before stated, in a face to face relation so that they normally assume the contacting position shown in Fig. 2.

Thus in the use of my invention, for instance, as a fastener for the rear portion of a collar, the plate 11, by slight separation from the plate 10 as seen in Fig. 1, may be pressed upwardly beneath the free lower edge of the rear separate section of material of a collar band, usually carrying the button-hole for the rear collar-button, and by releasing the plate 10, the spring 19 will force the plates toward one another and their roughened inner surfaces will engage the inner and outer faces of said separate section of material so as to tightly clamp the same.

The outer plate 10 carries a button-like engaging member which in the present instance, I have shown in the form of a shank 20 extending from its outer face and integral therewith, the outer end of the shank having a head 21 which is thus engageable with the button-hole of the collar, with the plates in the clamped position at the rear of the collar-band as above described, so as to securely hold the rear of the collar in a proper definite relation to the rear of the collar band, and which relation may obviously be varied with my improvement, that

2
is adjusted vertically where it is desired to either lower or elevate the rear of the collar. While I have thus fully described my invention and specified its use in one particular instance, it is obvious that my invention is capable of various uses and may be adapted to a variety thereof, where it is a consideration to employ a button or an engaging member of like nature, without perforation of the goods to form a button-hole as usual, or where slight adjustment in a quick, ready manner, is a consideration.

I claim:

1. A fastener of the character described, consisting of a pair of plates of substantially flatiron shape, disposed in face to face relation and having their adjacent faces roughened, said plates having extensions at their larger endslapping one another in juxtaposed relation, a hinge pin extending through said extensions whereby to hingedly connect the plates, and having a rigid connection with one of the plates and a flat face between the extensions of the plates, a spring carried by the other of said plates and engaging the flattened face of the pin to normally shift the plates toward one another, and a button-like engaging member carried by one of the plates and projecting from the outer face thereof.

2. A fastener of the character described, consisting of a pair of plates of similar shape disposed in face to face relation and having their inner adjacent faces roughened, said plates being provided with extensions along one face, a hinge pin projecting through said extensions to hingedly connect the plates, said hinge pin being in rigid relation to one of said plates and having an intermediate flat face, a spring carried by the other of said plates and engaging the flat face of the hinge pin to normally urge the plates toward one another, and a button-like engaging member extending from the outer face of the first-named plate. 45

3. A fastener of the character described, consisting of a pair of clamping plates, a hinged connection between said plates including a hinge pin, and a flat spring carried by one of said plates and having its free end engaging said hinge pin to normally urge the plates toward one another, one of said plates having an integral shank projecting from its outer face and headed, for the purpose described.

ALFRED GRIFFITH.
